Clarence A. O'Brien

Attorney

UNITED STATES PATENT OFFICE

2,297,151

CLOTHESLINE FASTENER

Edward Jabs, Cleveland, Ohio

Application December 10, 1941, Serial No. 422,436

1 Claim. (Cl. 24—134)

My invention relates to improvements in fasteners for clothes, or wash, lines, the principal object in view being to provide a simply constructed, easily operated device of this character for fastening one end of a clothes, or wash, line to a wall, or the like, and which will not cut nor abrade the line nor permit the same to work loose.

Other and subordinate objects are also comprehended by my invention, all of which, together with the precise nature of my improvements, will be readily understood when the succeeding description and claim are read with reference to the drawing accompanying and forming part of this specification.

In said drawing:

Figure 1 is a view in side elevation illustrating my improved fastener applied.

Figure 2 is a view in longitudinal section taken on the line 2—2 of Figure 3 and showing the parts in fastening position in full line and in unfastening position in dotted lines.

Figure 3 is a view in edge elevation,

Figure 4 is a view in perspective of the bell crank lever,

Figure 5 is a view in side elevation of the clamping cam, and

Figure 6 is a view in edge elevation of said cam.

Reference being had to the drawing by numerals, my improved fastener comprises an elongated frame 1 of bar-like metal having a hook-shaped front end 2 opening rearwardly and a rear hook-shaped end 3 opening forwardly and reduced in width, edgewise, the sides of the front end 2 being spaced apart further than those of the rear end 3. The rear end 3 is apertured adjacent the bight thereof, as at 4, for the extension of an eye bolt 5 therethrough for securing the fastener to a fixed part, such as a wall 6 to swing vertically thereon.

A bell crank lever 7 is pivoted at the angle thereof, on a transverse pivot 8 and in the rear end 3 forwardly of the aperture 4 for swinging in opposite directions in said end, said lever providing an operating arm 9 extending out of said end and a forwardly extending clamping arm 10. The forwardly extending arm 10 terminates in a pair of laterally spaced flat lugs 11, 12 oppositely extending upon opposite sides of the longitudinal center of said arm, the lug 11 forming a key lug and the other lug a clamping lug.

An oblong clamping cam 13 is pivoted at one end in the front end 2 of the frame 1 to extend rearwardly. The cam 13 has a grooved rear end 55

14 eccentric to the axis of the cam and provided with a central concave notch 14' adapted for cooperation with the clamping lug 12, said cam also having a forked rear end extension 15 on one side thereof in which the key lug 11 extends, the arrangement being such that under swinging of the operating arm 9 rearwardly of the frame 1, the clamping arm 10 will be swung toward the clamping cam 13 by sliding and pivoting movement of the key lug 11 in the forked extension 15, and the clamping lug 12 and grooved rear end 14 of the clamping cam 13 will be opposed in substantially dead center relation. Conversely, swinging of said operating arm 9 forwardly will result in the clamping arm 10 being swung away from the clamping cam 13 and said cam away from said arm in separated relation, as shown in dotted lines in Figure 2. A bulge 16 is provided on the frame 1 forwardly of the pivot 8 for reinforcing purposes. The beak 17 of the forked front end 2 is curved outwardly for clearance for a line inserted in between the clamping cam 13 and the clamping lug 12. A length of rope 18, or cord, may be fastened in an end eye 19 formed in the operating arm for pulling on said arm.

In the use and operation of the described fastener, a line 20 fixed at one end, as at 21, to a stationary part 22 is pulled substantially taut over the clamping cam 13 and inserted between the latter and the clamping lug 12, said line seating in the groove 14 of the clamping cam, all with the parts in the position shown in dotted lines in Figure 2. The operating arm is next swung rearwardly to cause the clamping lug 12 and the rear end 14 of the clamping cam 13 to move toward dead center relation and to clamp the line therebetween and in the concave notch 14'.

As will be clear, the grooved rear end 14 of the clamping cam 13 and the clamping lug 12 provide broad clamping surfaces which will not mar, cut or abrade the line and pull on the line forwardly of the fastener, will tighten the parts of the fastener in a manner which has been substantially described.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the subjoined claim.

What I claim is:

In a clothes line fastener, an elongated frame

of bar-like metal having front and rear hook-shaped ends opening toward each other, the rear end having an eye bolt swiveled thereon for attachment of said rear end to a fixed support, a bell crank lever including an operating arm extending laterally out of the rear end and a forwardly extending clamping arm, said lever being pivoted at the juncture of said arms in said rear end for rocking movement in opposite directions, an oblong clamping cam pivoted at one end in the front end of the frame to extend rearwardly and for rocking movement in opposite directions, and having a forked rear end extension at one side thereof and a groove in the rear

5 end for receiving the line, a clamping lug extending laterally from said clamping arm for coaction with said rear end of the clamping cam and a second lateral lug extending from the clamping arm into said forked extension whereby under rocking of said lever in one direction the grooved end of the clamping cam and said clamping lug will be rotated toward each other to clamp the line therebetween, said end of said cam and clamping lug being constructed and arranged to rotate toward a dead center relation to clamp said line.

EDWARD JABS.
